M. P. APPELL,
TIRE SAVING DEVICE FOR AUTOMOBILES,
APPLICATION FILED DEC. 13, 1915.

1,246,838.

Patented Nov. 20, 1917.

WITNESS:
John W. Hunter

INVENTOR:

Martin P. Appell,

UNITED STATES PATENT OFFICE.

MARTIN P. APPELL, OF NEAR GALVA, ILLINOIS.

TIRE-SAVING DEVICE FOR AUTOMOBILES.

1,246,838.

Specification of Letters Patent. Patented Nov. 20, 1917.

Application filed December 13, 1915. Serial No. 66,595.

To all whom it may concern:

Be it known that I, MARTIN P. APPELL, a citizen of the United States, residing near Galva, in the county of Henry and State of Illinois, have invented a new and useful Tire-Saving Device for Automobiles, of which the following is a specification.

My invention relates to shoes or like covers which may be applied to or over the usual tires or casings of an automobile or other vehicle equipped with pneumatic or similar tires.

The principal object of the invention is to generally simplify and improve tire shoes and the means for securing them on the tires.

It is an object to so construct the shoes that the usual tire-chains may with ease and facility be placed over them and secured directly thereto.

It is another object to provide means whereby the shoes may be made to fit casings of different circumferences.

Another object is to so construct each shoe and the shoe-securing elements that they may quickly be secured to or removed from a casing, and further that they may be adjusted and drawn taut thereon.

Minor objects will presently appear.

The invention consists, substantially, in the improvements hereinafter described.

By way of example a tire-shoe constructed according to my invention is herein described with reference to the accompanying drawing, in which:

Figure 1 is a side elevation of an automobile wheel equipped with a preferred embodiment of my invention;

Fig. 2, a transverse sectional detail, partly in elevation and partly broken away;

Fig. 3, a fragmental detail in side elevation, showing the manner of connecting the parts of the improvements and showing also a means for connecting a tire-chain to the shoe;

Fig. 4, a section, taken in the line 4-4 in Fig. 3;

Fig. 5, a fragmental detail in side elevation, showing the tire-chain attached; and

Fig. 6, a transverse section of a modified form of shoe.

In said drawings 2 designates a wheel having a rim 3, a tire-casing 4, and an inner tube 5.

The shoe proper of my improvement consists of a strip 6 of any suitable wear-resisting material and is of such length that it will encircle, and of such width that it will substantially embrace the sides of the casing. The ends are preferably overlapped, as indicated by 7. Throughout the length of each of its longitudinal edges runs an eye 8 in which is slidably seated a cable 9 or other suitable securing means. A series of eyes or perforations 10 is formed in each longitudinal edge of the shoe, just outward relative to each of the eyes 8. The shoes may be constructed in any of a great many of suitable manners, another of which is illustrated in Fig. 6, wherein it is shown as a strip of material, the edges of which are turned back upon the body or main portion and there riveted, as shown at 11, whereby eyes 8' are formed. The shoe is here numbered 6'.

12, 12 indicate plates having each an angularly arranged projection 13 provided with an eye 14, and each plate is secured to and near one edge and end of the shoe, as by rivets 15. Also each plate 12 is provided with an eye 16 for the passage of the cable 9—see Figs. 3 and 4. 17, 17 indicate plates each secured to the other end of the shoe by rivets 18 or otherwise, and each is provided with a series of apertures 19 any of which is adapted for the engagement of one end of a hook 20, the other end threaded end of which is adapted to pass through the eye 14. 22 indicates a tensioning-nut and 23 a lock-nut, both on said threaded end. The link 17 has also an eye 17' for the passage of the cable 9.

24, Fig. 5, indicates a tire-chain well known in the art. For securing it to the shoe and cable I provide, preferably, key-ring links 25, each of which is adapted to pass through a link of the tire-chain 24 and through one of the apertures 10 in the shoe 6, thus embracing and indirectly engaging the cable 9.

After placement of my improvements, in an evident manner, upon the tire-casing, the butt end of each hook 20 is engaged with a desired one of the holes 19 in the plate 17 and its threaded end 21 passed through the aperture 14 in the projection 13. The tensioning-nut 22 is then threaded onto said end 21 and drawn taut, whereupon the lock-

nut 23 is similarly placed and drawn to effectively lock the parts snugly and firmly upon the casing 4. This arrangement serves not only to protect the casing and prevent its wear, but also it may be used with success upon demonstrating-cars or other cars the tires of which it is adapted to keep clean. It will be evident, of course, that a single-length shoe may be used on tires having different circumferences, this provision being afforded by the holes 19 and hooks 20. Other adjustments and tightening may be effected by the elements 13, 20 and 22. The ends of the cables being bent sharply at the point where they enter the eyes 16 and 17, and they being drawn taut, causes said ends to be frictionally locked. Any other means for securing these ends may of course be employed.

20 On bad roads it is desirable to use safety-chains. When this is done each thereof is to be positioned in the usual manner, but over the shoe. The links or loops 25 or any other suitable securing means are then 25 engaged as hereinabove described, with the holes 10 and the links of the chain 24, as shown in Fig. 5.

It will of course be evident that my improvements may be used on the wheels of 30 motorcycles, bicycles, etc., and on tires of types other than the one shown.

Having thus described the nature of my improvements and having shown a pre-

ferred and one modified type thereof, I claim as new the following, to-wit:

1. The combination with a vehicle-wheel, of a shoe encircling it and having a series of perforations near each of its longitudinal edges, cables engaged each with a longitudinal edge portion of the shoe, means for securing the ends of the cables, a plurality of key-ring links each oppositely arranged pair of which is passed through an oppositely arranged pair of said perforations and embracing the adjacent cable, and a tire-chain embraced by said links.

2. A tire-shoe consisting of an elongated strip, cables engaged each with a longitudinal edge portion of the shoe, a plate secured to one end of the shoe and having a cable-receiving eye and an angularly arranged projection having an eye, a plate secured to the other end of the shoe and provided with a cable-receiving eye and with a series of apertures, a threaded hook one end of which is adapted to engage any of said apertures and its other end to pass through the eye in said angularly arranged projection, and a nut engaging the threads on said hook.

In testimony that I claim the foregoing as my invention I hereunto subscribe my name, at Galesburg, in the county of Knox and State of Illinois, this eighth day of December, 1915:

MARTIN P. APPELL.
